UNITED STATES PATENT OFFICE.

JEPHTA G. HOLLINGSWORTH, OF KANSAS CITY, MISSOURI.

DESIGN FOR AN INDIVIDUAL DENTAL-PLATE CLEANER.

53,366.

Specification for Design.

Patented May 27, 1919.

Application filed November 29, 1918. Serial No. 264,742. Term of patent 14 years.

To all whom it may concern:

Be it known that I, JEPHTA G. HOLLINGSWORTH, a citizen of the United States, and a resident of Kansas City, in the county of Jackson and State of Missouri, have invented a new, original, and ornamental Design for an Individual Dental-Plate Cleaner, of which the following is a specification, reference being had to the accompanying drawing, forming part thereof.

The said drawing represents a perspective view of an individual dental plate cleaner embodying my new design.

I claim:

The ornamental design for an individual dental plate cleaner as shown.

JEPHTA G. HOLLINGSWORTH.

Witnesses:

KENNETH M. THORPE,
GEO. Y. THORPE.
